UNITED STATES PATENT OFFICE.

JOHN J. ENGEL, OF MOUNT OLIVER, PENNSYLVANIA.

HEATER.

No. 817,757.

Specification of Letters Patent.

Patented April 17, 1906.

Application filed October 24, 1904. Serial No. 229,733.

To all whom it may concern:

Be it known that I, JOHN J. ENGEL, a citizen of the United States, residing at Mount Oliver, in the county of Allegheny and State 5 of Pennsylvania, have invented certain new and useful Improvements in Heaters, of which the following is a specification, reference being had therein to the accompanying drawings, forming part of the specification, 10 in which—

Figure 1 is a central vertical section through my improved radiating-heater. Fig. 2 is a horizontal cross-section on the line II II of Fig. 1.

15 My invention refers to improvements in the class of radiating-heaters employing gaseous or fluid fuel, although it may by properly designing the combustion-chamber be adapted to any suitable solid fuel.

20 The device has in view the provision of a large radiating area for the flues, the construction and arrangement of flues whereby such radiation is increased and comparatively large surface incorporated within a reduced 25 compact structure, the construction of the flues whereby the circulation of the gases of combustion is partially arrested and caused to traverse a tortuous course together with various other features of improvement and 30 change as shall be more fully hereinafter set forth.

Referring now to the drawings illustrating the invention, 2 represents the outer inclosing shell of the heater, which may be cylindrical in form, as shown, or of any other suitable design. The cold air from the exterior is furnished by the usual intake-pipe 3, thereby providing a pure supply of air from the exterior of the building or, if desired, it may 35 be taken in through suitable apertures 4 at the base of the shell. The top of the shell 5 constitutes a supply-dome from which the heated air is carried off by the usual supply pipes or conduits located at intervals around 40 the drum, as shown. In the interior of the shell 2 and incorporated therewith at its base portion is a combustion-chamber 7 of any suitable form, within which is mounted a fuel-burner 8, to which fuel is supplied by valve-controlled pipe 9 or any other suitable means, the usual mixer 10 being preferably incorporated therewith.

45 11 is a door opening into the combustion-chamber by which the fuel may be ignited or access may be had to the interior at any time.

50 12 is a receiving-chamber for the products

of combustion, similar to the combustion-chamber and located within the upper portion of shell 2, as shown vertically above the combustion-chamber, being provided with an 60 outlet-flue 13, leading to any suitable conduit, as a chimney, arranged to carry off the burned gases. Between the combustion chamber 7 and the receiving-chamber and connected therewith are a series of flues 14, 65 preferably rectangular in form, as square or oblong, in the interior of which are located a series of oppositely-disposed baffle-plates 15, extending inwardly alternately from opposite sides or ends of the flue-walls, as clearly 70 shown in Fig. 1, the object of which baffle-plates is to partially arrest or oppose the upward flow of the gases of combustion and also to provide closely-adjacent numerous heat-absorbing elements. It will be readily seen 75 that as thus constructed the heat of the upwardly-flowing gases will be practically entirely abstracted in their circulation from the bottom to the top of the flues and that their passage therethrough will be materially 80 checked, and thus facilitate the objects in view, the gases finally passing outwardly from the flues into the interior of receiving-chamber 12. This receiving-chamber is provided with an additional baffle-plate 16, 85 sloping backwardly away from the exit-opening into flue 13, as shown, preferably slightly inclined and terminating within a short distance of the opposite wall of chamber 12, the object being to deflect the gases 90 away from the outlet-flue over toward such opposite side, causing them to completely traverse the entire upper area of the receiving-chamber both underneath and above the baffle-plate 16 before finally emerging into 95 the outlet-flue.

Both the combustion-chamber 7 and receiving-chamber 12 are provided with inner walls 17 and 18, providing a central air-cavity, as clearly shown. It will be seen 100 that the cold air entering the shell 2 from supply-pipe 3 or from any other source will circulate freely around the combustion-chamber both outside and inside, as indicated by arrows, and will also pass between 105 the closely-adjacent flues 14 in one direction or another, or both, in traveling up through the interior area of the shell. The air is thus brought into contact with all of the exposed surfaces of the combustion-chamber flues 110 and the receiving-chamber before finally emerging into the supply-pipes 6. The cir-

culation of the air may be readily controlled by the usual dampers or registers, and this portion of my invention is not new *per se*.

Having described my invention, what I claim is—

1. A heater consisting of a rectangular burner-chamber provided with a central rectangular air-opening, a burner located in the burner-chamber, a series of closely-adjacent rectangular flues having parallel sides connected with the burner-chamber, series of alternately-arranged baffle-plates within the flues, an upper rectangular receiving-chamber for the products of combustion connected with the upper ends of the flues, provided with an interior baffle-plate, an outlet-flue, and a central rectangular air-opening, and an outer surrounding cylindrical casing provided with an air-inlet and one or more outlet openings, substantially as set forth.
2. In a heater, the combination of a rec-

tangular burner-chamber provided with a laterally-arranged door and a rectangular central air-opening, a burner located within the burner-chamber, a correspondingly-shaped upper receiving-chamber for the products of combustion provided with a deflecting baffle-plate, an outlet-flue, and a central rectangular air-opening, series of rectangular flues extending from the burner-chamber to the receiving-chamber rectangularly arranged with closely-adjacent parallel walls and interior baffle-plates, and an outer cylindrical casing provided with an air-inlet and one or more hot-air-outlet openings, substantially as set forth.

In testimony whereof I affix my signature in presence of two witnesses.

JOHN J. ENGEL.
